UNITED STATES PATENT OFFICE.

WILLIAM BUMM, OF PHILADELPHIA, PENNSYLVANIA.

SALT-CELLAR.

No. 900,911.

Specification of Letters Patent.

Patented Oct. 13, 1908.

Application filed November 27, 1907. Serial No. 404,133.

To all whom it may concern:

Be it known that I, WILLIAM BUMM, a citizen of the United States, residing at Philadelphia, in the county of Philadelphia and 5 State of Pennsylvania, have invented certain new and useful Improvements in Salt-Cellars, of which the following is a specification.

This invention relates to saltcellars, the object being, to provide a saltcellar which is 10 so constructed that the salt therein will flow readily out of the same, thereby overcoming the difficulties now existing with saltcellars when used in damp climates.

Another object of my invention is to provide a saltcellar with flexible body, whereby 15 it can be readily squeezed, so as to loosen the salt and force the same out through the perforated cap.

A further object of my invention is, to 20 provide a saltcellar which is very neat in appearance, and one which is exceedingly simple and cheap in construction.

Another object of my invention is, to so 25 connect the body of the saltcellar to the base and neck, that it can be readily removed when desired.

These objects are obtained by the novel arrangement and construction of parts hereinafter fully described and shown in the 30 accompanying drawings, in which:

Figure 1, is a perspective view of my improved saltcellar. Fig. 2, is a vertical section through the same, and, Fig. 3, is a perspective view of the saltcellar, the cap and 35 body being detached.

Referring to the drawings, A indicates a base which is formed of any suitable metal, and is provided with oppositely disposed upwardly projecting rods B, on the upper ends 40 of which is secured a neck C, which is provided with an internally threaded portion C' and an annular groove C², for the purpose hereinafter fully described.

A cap D provided with a threaded neck 45 portion is arranged within the neck C, the cap being provided with perforations, so that the salt can readily pass through the same. An annular flange A' is formed on the base over which is adapted to place the 50 lower portion of the tube E, forming the

body portion of the receptacle for holding salt. The tube being secured thereon by a ring F, which securely binds it to the flange A'. The upper end of the tube E extends into the annular groove C² of the neck C and is secured therein by a ring G, which fits within the groove and locks the tube 55 therein.

The body is formed of any flexible material, such as cloth or rubber, whereby it will give when it is squeezed. In operation the cap is removed and the receptacle is filled with salt and the cap is then replaced, and it will be seen that by pressing on the sides of the body, the salt therein will be broken 60 up if it has become hardened, and at the same time will be forced out through the neck, thereby overcoming the difficulties of saltcellars now in use, as the salt in the same becomes lumpy or very damp when 65 used in damp climates, so that it is impossible to use a saltcellar as the salt therein will not pass out through the perforations in the cap.

From the foregoing description it will be 70 seen that I have provided a saltcellar which is provided with flexible sides, so that by pressing on the same, the salt will be forced outwardly when the saltcellar is inverted.

Having thus described my invention what 80 I claim as new and desire to secure by Letters Patent is:

1. A saltcellar comprising a base provided with rods carrying a neck provided with a perforated cap, an annular flange formed on 85 said base, said neck being provided with an annular groove, a flexible body formed of a tube having its upper end arranged in said groove and its lower end arranged over said flange, and means for securing said tube in 90 said groove and over said flange.

2. A saltcellar comprising a base provided with rods carrying a neck, a cap arranged on said neck, a flexible tube connecting said base and neck, and means for securing said 95 tube to said base and neck.

3. A saltcellar comprising a base provided with an annular flange on its top, oppositely disposed rods arranged on said base, a neck secured to the upper end of said rods, a cap 100

fitting within said neck, said neck being provided with an annular groove, a tube made of flexible material connecting said base and neck, the upper end of tube being secured in said groove by a ring and the lower end of said tube being secured over said flange by a ring, for the purpose set forth.

In testimony whereof I have signed my name to this specification in the presence of two subscribing witnesses.

WILLIAM BUMM.
